DESIGN FOR A MOTOR CASING

Joseph H. Cohen, Bridgeport, Conn., assignor to Casco Products Corporation, Bridgeport, Conn.,
a corporation of Connecticut

Application July 27, 1940, Serial No. 93,968

Term of patent 14 years

To all whom it may concern:

Be it known that I, Joseph H. Cohen, a citizen of the United States, residing at Bridgeport, in the county of Fairfield and State of Connecticut, have invented a new, original, and ornamental Design for a Motor Casing, of which the following is a specification, reference being had to the accompanying drawing, forming part thereof.

Figure 1 is a side elevational view of a motor casing, showing my new design.

Fig. 2 is a front elevational view of the same.

Fig. 3 is a rear elevational view of the same.

I claim:

The ornamental design for a motor casing, as shown.

JOSEPH H. COHEN.
